UNITED STATES PATENT OFFICE

CHARLES ALFRED GESNEL, OF BOURG, FRANCE

SIFTING MACHINE

Application filed April 23, 1928, Serial No. 271,998, and in France May 7, 1927.

Sifting machines are known, which comprise blades or vanes which project the material being treated at a certain angle against a screen or mesh, but these prior art machines have no means to permit this angle to be varied without a complete modification of the machine itself. Moreover, in existing machines the blades are all of uniform length so that, in operation, the material under treatment drops to the bottom of the machine and is projected only against the lower perforated surface of the screen.

The object of the present invention is to obviate the disadvantages of existing machines, and it relates to a sifting machine characterized by the provision of adjusting members arranged, for example, at the ends of the blades. These adjusting members regulate the direction of projection of the material against the screen, so that by a simple adjustment of the machine without a reconstruction or rearrangement of the parts thereof, the degree of fineness of the sifting action may be changed at will. The blades are also of different lengths, which permits of projecting the material in different planes against the screen and more regularly distributing the material on the screen; in this manner, the efficiency of the screen is increased.

The purpose of the invention is to ensure a cleaning, as uniform as possible, of the sieves, in such a manner that their choking up may be eliminated.

The sifting machine, forming the subject of the invention, allows these various objects to be attained by means of essential features described in the specification below, and in the claim annexed to that specification.

The preferable embodiment of the invention is shown as an example on the drawings appended wherein:—

Figure 1 is a part elevation and a part vertical axial section of a sifting machine according to the invention.

Figure 2 is a plan of this machine.

Figures 3 and 4 are two half sections of this machine respectively according to the lines 3—3 and 4—4 of Figure 1.

Figure 5 is a half elevation and half longi-

tudinal axial section of the first stage of the turbine.

Figure 6 is a plan view of this first stage. Figure 7 is a part section of the extremity 55 of a blade.

Figure 8 is a diagram showing the various heights of the blades of this turbine.

Figure 9 is a developed view of the sifting gauze of the first stage of the turbine.

Figure 10 is a section of this gauze according to the line 10, 10 of Figure 9.

Figure 11 is a section on a larger scale of the vibrator of the sieve.

Figure 12 is a half elevation and a half longitudinal section of the second stage of the turbine.

Figure 13 is a plan view of the second stage.

Figure 14 is a section of one of the vibrators of this second stage.

Figure 15 is a half elevation and a vertical axial half section of the third stage.

Figure 16 is a plan of this third stage.

Figure 17 is a section of the vibrator of this third stage.

Figure 18 is a detail view of one end of a blade or vane.

The apparatus constituting the preferable embodiment of the invention, comprises three stages viz, 1¹, 1², 1³ of turbines on a common vertical shaft 2, above each of which a funnel 3¹, 3², 3³ is placed which guides the material in the direction of the axis. The top funnel 3¹ ensures the charging, whilst the funnels 3², 3³ lead the residue from the preceding turbine respectively to the second and third turbine.

Below the lower turbine a receptacle 7 is provided, which collects the residue of the upper turbines, it being emptied by the action of the blade 8 (Figure 4) through a lateral channel 9.

The apparatus is encircled by a cylinder 10 which terminates in a discharge funnel 11.

The first turbine 1¹ consists of the curved winglets or blades 4 carried on a plate 5 (Figure 3) and it is encircled by a stationary cylindrical sieve gauze 6¹. The details of this first stage are represented in the Figures 5—8.

It will be particularly noted in Figure 8

that the blades of the turbine are of three different heights which allows the formation of a series of channels. The material to be sifted, having been charged into the upper funnel 3¹ at the top of the apparatus, reaches the upper turbine 1¹ which projects it with force against the corresponding gauze 6₁, in a direction which depends on the inclination of the blades 4 and on the speed of rotation, and which can consequently be regulated as desired. The gauze functions thus, as regards the particles of the material, as if the holes were flattened and the sifting is much finer. In accordance with my invention, each blade 4 carries at its free end an interchangeable sheet metal adjusting member 60, which may be of different shapes, thus permitting variation of the angle at which the material is projected against the screen and consequent modification of the fineness of the sifting action to be effected, without any need to change the machine.

The materials that pass through the gauze cloth 6¹ of the first turbine pass to the discharge funnel 11; the residue is passed on to the second turbine 1²; this second turbine consists of a series of inwardly curved arms 12 which receive fluid under pressure from central boxes 13, which are themselves fed by the hollow shaft 14. A funnel 3² leads the residue of the first turbine to the second one. The material arriving at the turbine 1² is projected towards the periphery and subjected to the action of the jets issuing from the pipes 12 which project it on the cloth 6². The formation of lumps of fatty powder is thus eliminated.

The fluid employed may be, according to the circumstances either air or water.

40 The residue that has not passed through the gauze 6² of the second turbine 1² is collected by the funnel 3³ and reaches the third turbine 1³ which is similar to the second turbine 1² except that the pipes 12 are radial. 45 But by the effect of the rotation, as is well known, the speed of the fluid issuing from the said pipes is inclined in relation to the gauze 6³.

Each turbine stage 3¹, 3², 3³ is provided 50 with automatic means of cleaning the sieve gauzes 6¹, 6², 6³.

The first stage 3¹ is for this purpose arranged as follows:—vibrators 23 are fixed at various places on a blade of steel 24, which 55 is itself fixed at 25 to the rigid frame 22 of the gauze cloth 6¹.

Each of the vibrators consists (Figure 11) 60 of a spring lamination 23 which is connected by means of the rivets 26 to the steel blade 24.

65 This spring lamination 23 is curved at 36 and forms a hook 37 which is the point of contact.

On the other hand a fork 27; fitted to the 70 extremity of each blade 4 and connected with it by rivets 30, carries at its extremity a

spindle 31 on which a little roller 32 is placed, with a considerable play *j*, the diameter of that spindle being much smaller than the bore of the roller.

70 Thus the roller 32 sits loose on its spindle, and it is only the centrifugal force that causes its touch action as soon as it encounters the vibrators 23.

75 During each revolution, the vibrator or vibrators are actuated and transmit their vibrations to the sieves. It is therefore possible, in employing 2, 3, 4 or a larger number of vibrators per blade, and in running them at speeds of from 800 to 900 revolutions per minute, to obtain from 1800–3600 80 and more impacts per minute and thus maintain a quick and constant vibration of the sieves; their meshes therefore always remain clear, and the sifting action is consequently certain and the output is a maximum. 85

The second stage 3² of the turbine has an absolutely similar arrangement, for the purpose of ensuring the cleaning of the gauze sieves 6². The vibrator, however, details of which are shown in Figure 14, consists of a flat spring 40 riveted at one of the extremities, at 41, on the steel blade 24, and at the other extremity at 42 on a small rigid lever 43, provided with a raised part 44. By pressing on this raised part the extremity 42 is 95 lifted off the spring 40 which snaps back into its place, as soon as 44 is released.

The third stage 3³ of the turbine has a similar arrangement as regards the cleaning of the gauze sieves 6³. The vibrator (Figure 100 17) comprises a lever 47, pivoted or articulated on the axis 48, and under the influence of a spring 49 with long free branches 49¹, 49² which are fixed, one on 24 and the other on the lever 47. In pressing on the extremity 50 of the lever 47, the spring 49 is tensioned whilst the extremity 51 of this lever 47 is lifted; this extremity shoots back into its place as soon as the extremity 50 of the lever 47 is released. 105

Claim:

In a sifting machine, the combination of a sieve, means to project the material being treated at a certain angle against said sieve, interchangeable means to vary said angle at will, means to receive the particles which have traversed the sieve and means to receive the residue of the material which has not traversed the sieve. 115

120 In testimony whereof I affix my signature.

CHARLES ALFRED GESNEL.
